(57) **CLAIM**

The ornamental design for a spa handrail, as shown and described.

DESCRIPTION

FIG. 1 is a front-top-right perspective view of a spa handrail showing my new design;

FIG. 2 is a rear-bottom-right perspective view thereof;

FIG. 3 is a rear elevation view thereof;

FIG. 4 is a front elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a detail view taken from area 9 of FIG. 2, showing the handle of the spa handrail in a first position; and,

FIG. 10 is another detail view showing the handle of the spa handrail in a second position.

The broken lines in the figures illustrate portions of the spa handrail that form no part of the claimed design. The portions of the spa handrail that are not visible in the figures form no part of the claimed design.

1 Claim, 9 Drawing Sheets
